CLAIM

The ornamental design for patient medical monitor, as shown and described.

DESCRIPTION

FIG. 1 is a front perspective view of a patient medical monitor showing my new design;

FIG. 2 is a front perspective view of a second embodiment of the patient medical monitor, wherein the only difference resides in the patient boxes;

FIG. 3 is a left side elevational view thereof;

FIG. 4 is a rear elevational view thereof;

FIG. 5 is a back plan view of FIG. 1; and,

FIG. 6 is a front elevational view thereof, with the patient boxes omitted for convenience of illustration.

FIG 1

FIG 2

FIG 3

FIG 4
